(57) **CLAIM**

The ornamental design for an air-conditioning unit, as shown and described.

DESCRIPTION

FIG. 1 is an upper perspective view of an air-conditioning unit design;

FIG. 2 is a lower perspective view of the design of FIG. 1; FIG. 3 is a top plan view of the design of FIG. 1;

FIG. 4 is a bottom plan view of the design of FIG. 1;

FIG. 5 is a left side view of the design of FIG. 1;

FIG. 6 is a right side view of the design of FIG. 1;

FIG. 7 is a rear elevation view of the design of FIG. 1; and, FIG. 8 is a front elevation view of the design of FIG. 1.

The broken lines illustrating portions of the air-conditioning unit form no part of the claimed design.

1 Claim, 8 Drawing Sheets
